ROTARY FLUID PRESSURE ENGINE

Edward Harry Johnson, Coventry, England, assignor to
The Keelevite Company Limited, Coventry, England, a
company of Great Britain

Application November 21, 1951, Serial No. 257,446

11 Claims. (Cl. 103—125)

This invention relates to rotary fluid pressure engines, whether they be pumps or motors, of the kind comprising a casing in which is provided an annular blade chamber, a rotor having blades which extend across the blade chamber so as to make a sealing fit with the inner and outer circumferential walls of the blade chamber relatively to which the rotor rotates about the axis of the blade chamber, at least one rotary abutment extending across the blade chamber between inlet and outlet ports with its axis parallel to the axis of the rotor lying in and making a sealing fit with the walls of an abutment chamber consisting mainly of an abutment recess, hereinafter called the larger abutment recess, in the one of the circumferential walls of the blade chamber, but also partly of an abutment recess, hereinafter referred to as the smaller abutment recess, in the other circumferential wall of the blade chamber, the abutment being provided with pairs of diametrically opposite recesses in its periphery all of the same circumferential dimensions, two or more of such recesses constituting blade-receiving recesses each of which during rotation of the abutment comes into position to receive a blade and permit it to pass the abutment as the blade during its rotation comes to the part of the blade chamber across which the abutment extends, and two pressure balancing recesses provided in the circumferential surface of the larger abutment recess and lying diametrically opposite the parts of the abutment which are exposed respectively to the pressure in the high and low pressure parts of the blade chamber, the area of each pressure balancing recess measured at the circumference of the abutment being equal to the diametrically opposite area exposed to the interior of the blade chamber and such that it communicates at all times with one or other of the recesses in the abutment and each recess in the abutment being connected by a passage in the abutment with the diametrically opposite recess.

In certain applications of pumps and motors of the above kind it is important that the flow of fluid through the pump or motor shall bear and maintain a close relationship to the angle of rotation of the rotor even at very low speeds, and that this relationship shall be maintained throughout each individual revolution of the rotor.

It will be appreciated that the maintenance of such an exact relationship, especially at low rotational speeds, cannot be achieved if there are appreciable variations in the rate of leakage through the clearance spaces of the pump or motor exposed to the pressure in the working chamber during each revolution, and it is the object of the present invention to provide an arrangement, which will tend to reduce to a minimum variations in the relationship between fluid flow through the pump or motor and rotation of the rotor and thus be particularly but not exclusively applicable to so-called sensitive pumps and motors, that is pumps and motors in which it is important to maintain a substantially fixed relationship between rate of fluid flow and angle of rotor rotation.

To this end according to the present invention the dimensions of the inlet and outlet ports of a pump or motor

of the kind referred to where they open into the blade chamber are such and/or the inner wall of the blade chamber and/or larger abutment recess adjacent to such ports is so cut away that for all rotational positions of the blades and abutment the total circumferential lengths of sealing contact between the blades and the inner and outer walls of the blade chamber and between the abutment and each of the abutment recesses remain unchanged throughout the rotation of the parts.

Thus the arc over which extend the parts of the inner and outer circumferential walls of the blade chamber with which the blades in their travel make sealing contact is equal to the angle between the blades in the case of a two blade rotor or between any two adjacent blades in rotors having more than two blades.

Further in some cases in order to maintain the sealing area between the abutment and the larger and smaller abutment recesses respectively constant throughout the rotation of the abutment, it may be necessary to provide in each of these recesses cut-away parts constituting non-sealing areas of the same width as each of the areas of the abutment exposed to the pressure in the blade chamber, that is to say the area of the communicating opening between either side of the blade chamber and the abutment chamber. While moreover for pressure balancing or other reasons it may be necessary or desirable to provide certain non-sealing areas on the circumferential surface of the abutment between the blade-receiving recesses. Thus in preferred arrangements in a pump or motor of the kind referred to according to the invention the surface of the abutment chamber constituted by the larger and smaller abutment recesses is divided circumferentially into a series of equally spaced sealing areas of equal circumferential length separated by equally spaced non-sealing areas and the circumferential surface of the abutment is divided circumferentially into a series of equally spaced sealing areas of equal circumferential width separated by equally spaced non sealing areas constituted wholly or as to some of them only, by the blade receiving recesses, the relative circumferential dimensions of the sealing and non sealing areas respectively on the abutment and the surface of the abutment recesses being such that at each moment during rotation when any sealing area on the abutment breaks engagement with a sealing area in either of the abutment recesses, the abutment sealing area in rear thereof in the sense of rotation comes into the position in which it has its maximum area of engagement with the appropriate sealing area in the abutment recess.

It will be seen that the arrangement so far described ensures that the circumferential sealing areas between the high and low pressure parts of the pump or motor both in the blade chamber and in the abutment recesses remain constant throughout rotation of the rotor and abutment so that, under any given conditions the rate of leakage through the circumferential seals tends to remain constant and thereby to maintain an exact relationship between fluid flow and angle of rotor rotation throughout each revolution of the rotor.

It also tends to ensure substantially constant leakage through the clearance spaces between the blades and the ends of the working chamber with which they make a sealing fit by providing a constant area of seal subject respectively to the high and low pressures at these points. There are, however, other working clearances the areas of which subject to the higher pressure vary during operation, namely the arcuate sealing area between the abutment and the smaller abutment recess at the point where the abutment enters the working chamber, since this arcuate sealing area will, when a recess in the abutment is traversing it and is in communication with the high pressure side of the working

chamber, have a relatively large area subject to high pressure while when a recess in the abutment is traversing it and comes into communication with the low pressure side of the working chamber the arc will be mainly subject to low pressure. Similarly with some constructions the length of the circumferential sealing surface between the end of the abutment and the wall of the casing through which it or a shaft driving it enters the abutment chamber which is subject to the higher pressure may vary with rotation of the abutment due to the arrangement and spacing of the recesses in the abutment which at different times are in communication respectively with the high pressure and low pressure sides of the working chamber. This latter difficulty can be reduced by providing a number of blade-receiving recesses in the abutment, for example four, such that at all times the mean pressure in the recesses in the abutment is constant whereby on sum there is no leakage to or from the abutment chamber although there may be a constant leakage between the various recesses across the end face of the abutment chamber.

Moreover, a circumferential seal may be provided around the shaft by which the abutment is driven and which passes through the end face of the abutment chamber.

In order to ensure still further that little change in mean leakage shall occur due to the variations in the length of the sealing paths exposed to pressure during rotation of the rotor and abutment, the pump or motor will preferably be provided with a closed casing filled with the working fluid, into which casing the various working clearances open so that any leakage through a clearance area for the moment subject to high pressure tends to build up pressure in the casing, while leakage through a clearance area subject to low pressure tends to permit leakage from the casing. Thus the pressure in the casing tends to vary according to the relative lengths of leakage paths from the high pressure side to the casing and from the casing to the low pressure side, and this being so the total rate of leakage tends to remain constant.

Various forms of hydraulic pump or motor incorporating the invention are illustrated by way of example in the accompanying drawings, in which

Figure 1 is a sectional side elevation of one form of pump or motor according to the invention having a four blade rotor,

Figure 2 is a cross section on the line 2—2 of Figure 1,

Figure 3 is a similar view to Figure 2 showing how the invention may be applied to a pump or motor having a two blade rotor, and

Figure 4 is a similar view to Figure 2 showing how the invention may be applied to a pump or motor having a three blade rotor.

In the construction shown in Figures 1 and 2 the pump or motor comprises a block A constituting the body of the pump or motor proper sandwiched between two end cap or casing members B and C which in conjunction with the circumferential part of the block A form a fluid tight casing enclosing the working parts of the pump or motor proper.

The block or body part A has formed therein two parallel intersecting cylindrical bores D and E adjacent end portions D¹ and E¹ of which constitute respectively the outer circumference of the working chamber D² and the larger abutment recess.

Secured by bolts F to one end of the block A within the casing part B is an end member F¹ having a part cylindrical projection F² which projects into and makes a fluid tight seal with part of the circumference of the bore D and has a part of reduced diameter F³ at its end which constitutes the inner circumferential wall of the working chamber D².

Inlet and outlet passages passing through the block A communicate with the working chamber D².

The projection F² is less than a complete cylinder in

5 that it has an arcuate recess E² in its circumferential surface constituting the smaller abutment recess and therefore having a part cylindrical surface which constitutes in effect a continuation of the part cylindrical surface of the larger abutment recess E¹.

Also secured to the end face of the block A enclosed by the casing part B is an end member G having a cylindrical part G¹ at one end which projects into the bore E, regarding this as including the recess E² and forms one end face of the abutment chamber.

The opposite end face of the abutment chamber is formed by an end plate H secured to the face of the block A within the casing part C and having a hollow boss portion H¹ the bore of which is coaxial with the bore D¹ of the working chamber D² and includes a part H² which opens into the working chamber D² and has the same diameter as the outer circumference D¹ of the working chamber, and an outer part which is of somewhat larger diameter than the outer circumference of the working chamber.

Disposed coaxially with the working chamber D² and supported in bearings J at one end in the end member F¹ is a rotor shaft K carrying a rotor, K¹ having a cylindrical part K² making a close seal with the part H² of the bore 15 of the boss H¹ from which cylindrical part project four blades K³ of the cross sectional form shown in Figure 2.

The bore of the cylindrical part K² of the rotor makes a fluid tight seal with a ring F⁴ secured to the end of the part F³.

20 The rotor K¹ which is keyed to the shaft K, is supported in roller bearings J¹ so that the whole rotor shaft and rotor assembly K, K¹ is carried by the bearings J and J¹. The shaft K projects through a fluid tight gland K⁴ in the casing part C. Mounted in the abutment chamber 25 is a rotary abutment L of the cross sectional form shown in Figure 2 so as to have four blade-receiving recesses L¹, the abutment being mounted on an abutment shaft L² one end of which is supported in bearings L³ in the end member G while its other end has rigidly mounted thereon a gear wheel M supported in a bearing L⁴ in the member G. The gear wheel M meshes with a gear wheel N of the same pitch diameter on the rotor shaft K so that the rotor shaft K and abutment shaft L² during operation rotate in opposite directions at the same rotational speed. The arrangement is such that in known manner one of the blade-receiving recesses L¹ comes into position to receive a blade K³ and permit it to pass the abutment L each time a blade reaches the point in the working chamber D² across which the abutment L extends.

30 Formed in the abutment L are passages, O, O¹ connecting opposite blade-receiving recesses L¹ to one another and also passages indicated at O² and O³ in Figure 2 extending between diametrically opposite points in the circumferential surface of the abutment L disposed midway between the edges of adjacent blade-receiving recesses L¹.

35 Formed in the abutment receiving recesses E¹ and E² are grooves E³ each having a circumferential width equal to that of each of the areas E⁴, E⁵ over which the abutment is directly subject to the pressure in one side or the other of the working chamber D². The arrangement is such that each groove E³ is permanently maintained in communication with its diametrically opposite groove E³ or space E⁴ or E⁵ by the passages O, O¹, O² and O³. Moreover the dimensions are such that the circumferential width of each blade-receiving recess L¹ is equal to the sum of the circumferential width of each non-sealing groove E³ or space E⁴ or E⁵ and the circumferential width of each of the sealing surfaces L⁴ between adjacent edges of the grooves E³ and spaces E⁴, E⁵.

40 It will therefore be seen that as that abutment L rotates the length of circumferential seal between it and the surface of the smaller abutment receiving recess E² will remain constant and that similarly the total length of 45 circumferential seal between it and the surface of the

larger abutment receiving recess E^1 will remain constant and in such manner that the total circumferential length of sealing area between any two adjacent spaces subject respectively to inlet and outlet pressure remains constant. Each of the inlet and outlet passages D^3 and D^4 opens into the working chamber through a port having a circumferential width such that the edges of those ports remote from the abutment L lie in a plane containing the axis of the working chamber and at right angles to the common plane in which the axes of the rotor and abutment lie. It will be seen that with this arrangement the total area of seal between the outer circumferential surfaces of the blades at any moment occupying the working chamber D^2 and the outer circumferential wall of this chamber will be constant throughout the rotation of the rotor.

Similarly the inner circumferential wall of the working chamber is cut away as indicated at P so that its sealing surface terminates in the same place as the edges of the parts referred to above and the total area of the seal between the inner circumference of the working chamber therefore also remains constant throughout the rotation of the rotor.

In order still further to tend to maintain a constant degree of leakage through any clearance spaces during rotation of the parts of the pump or motor not only is the casing made liquid tight and filled with working liquid so that flow to and from it through any clearance spaces opening into it tends to be resisted by reason of the build up or reduction in pressure thus caused, but a fluid seal of some known type is provided around the abutment shaft as indicated at P^1 .

In the modified construction shown in Figure 3 the pump or motor might otherwise be of the same general construction as that shown in Figures 1 and 2 but the rotor has only two blades as indicated at Q , and the abutment R has therefore only two blade-receiving recesses as indicated at R^1 and in addition flats R^2 each of the same circumferential width as a recess R^1 . In this construction it will be seen that the diametrically opposite recesses R^1 and chambers formed by the flats R^2 communicate with one another through passages indicated at R^3 while grooves S are formed in the circumferential wall of the larger abutment receiving recess S^1 each of the same circumferential width as and lying diametrically opposite to one of the openings S^2 through which the abutment R is exposed to the pressures in the working chamber.

Each of the sealing surfaces S^3 which separate the grooves S and openings S^2 from one another has a circumferential width equal to the sum of the circumferential width of each of the recesses R^1 and the circumferential width of each of the sealing surfaces S^4 on the abutment which separate adjacent non-sealing recesses R^1 and flats R^2 from one another, while the circumferential width of the surface S^5 is equal to that of each of the surfaces S^3 . Thus, as the abutment R rotates the total circumferential length of sealing area between it and the smaller abutment receiving recess S^5 remains constant and the total circumferential length of sealing area between the abutment and the larger abutment recess S^1 remains constant in such manner that the circumferential length of each sealing area on the abutment between any space or chamber in communication with the high pressure side of the pump or motor and any adjacent space or chamber in communication with the low pressure side of the pump or motor remains constant.

It will moreover be seen that the edges of the inlet and outlet passages remote from the abutment extend to a plane containing the axis of the rotor and that the inner wall of the working chamber is also cut away as indicated at T so that in effect both circumferential walls of the part of the working chamber with which the blades make a sealing fit during their rotation terminate in the plane mentioned and hence the total effective length of

circumferential seal provided between the blades and the walls of the working chamber remains constant throughout the rotation of the rotor.

In the construction shown in Figure 4 the pump or motor might otherwise be similar to that shown in Figures 1 and 2 but has a three bladed rotor and a three recess abutment U and the abutment receiving recesses and the working chamber so formed as to provide the desired constant areas of circumferential seal. Thus in this construction the larger abutment receiving recess V is provided with two grooves V^1 each of the same circumferential length as and lying diametrically opposite to one of the spaces V^2 at which the abutment is exposed to the pressure in the working chamber, the grooves V^1 being separated by a circumferential sealing surface V^3 equal in circumferential length to each of the circumferential sealing surfaces V^4 between a groove V^1 and the adjacent space V^2 and also to the circumferential length of the smaller abutment receiving recess V^5 . The abutment in this construction has, moreover, formed on its circumferential surface three flats U^1 each of the same circumferential width as and diametrically opposite to one of the blade-receiving recesses U^2 with passages U^3 connecting each recess U^2 to its opposite flat U^1 . The circumferential width of each of the surfaces V^3 , V^4 and V^5 is equal to the sum of the circumferential width of each of the recesses U^2 and flats U^1 plus the circumferential width of any one of the sealing surfaces on the abutment between an edge of a blade-receiving recess U^2 and the adjacent edge of a flat U^1 .

In this construction also the inner and outer circumferential walls of the working chamber are formed so that the effective arc over which the surfaces which make sealing engagement with the blades during rotation of the latter subtend an angle of only 120° whereby the circumferential length of the total sealing surfaces between the blades and the walls of the working chamber remains constant throughout rotation of the rotor.

Although the invention has been described with particular reference to rotary pumps or motors of the kind referred to having a single abutment, it will be understood that it is equally applicable to such pumps and motors having two abutments and therefore two sets of inlet and outlet ports.

What I claim as my invention and desire to secure by Letters Patent is:

1. A rotary fluid pressure pump or motor of a type comprising a casing enclosing an annular blade chamber and having inlet and outlet ports, a rotor having blades which extend across the blade chamber and make a sealing fit with the inner and outer circumferential walls thereof relatively to which the rotor rotates about the axis of the blade chamber, and at least one rotary abutment with its axis parallel to the axis of the rotor extending across the blade chamber between the inlet and outlet ports and lying mainly within and making a sealing fit with an abutment receiving recess in one of the circumferential walls of the blade chamber and making a sealing fit with a second abutment receiving recess in the other circumferential wall of the blade chamber, said recesses being of the same diameter but subtending different arcs, the abutment containing in its periphery recesses at least some of which are arranged to come into position to receive a blade and permit it to pass the abutment as it comes to the point at which the abutment extends across the blade chamber, said peripheral recesses being arranged in diametrically opposed connected pairs constituting pressure equalizing openings between sealing parts of the abutment wherein the dimensions of the parts are such that the total circumferential widths of sealing engagement between the blades and the inner and outer walls of the blade chamber and between the abutment and each of the abutment receiving recesses remains unchanged throughout rotation of the rotor and abutment, whereby the rotational

speed of the rotor for a fixed rate of flow is maintained substantially constant at all angular positions of the rotor and vice versa.

2. A rotary pump or motor of a type comprising a casting enclosing an annular blade chamber having inlet and outlet ports, a rotor having blades which extend across the blade chamber and make a sealing fit with the inner and outer circumferential walls thereof, relatively to which the rotor rotates about the axis of the blade chamber, and a rotary abutment extending across the blade chamber between the inlet and outlet ports and making a sealing fit with a larger part-cylindrical abutment receiving recess in one of the circumferential walls of the blade chamber and a smaller part-cylindrical abutment receiving recess of the same diameter in the other circumferential wall of the blade chamber, the abutment having blade receiving recesses in its periphery disposed diametrically therein each of which comes into position to receive a blade and permit it to pass the abutment as it comes to the point at which the abutment extends across the blade chamber, wherein the arc over which extends the parts of the inner and outer circumferential walls of the working chamber with which the blades make a sealing fit during their rotation subtends an angle at the axis of the rotor evenly divisible by that between adjacent blades, while the surface of the abutment chamber constituted by the larger and smaller abutment receiving recesses is divided circumferentially into a series of equally spaced sealing areas of equal circumferential length separated by equally spaced non-sealing areas and the circumferential surface of the abutment is divided circumferentially into a series of equally spaced sealing areas of equal circumferential width separated by equally spaced non-sealing areas, the relative circumferential dimensions of the sealing and non-sealing areas respectively on the abutment and the surface of the abutment receiving recesses being such that at each moment during rotation when any sealing area on the abutment breaks engagement with a sealing area in either of the abutment receiving recesses, the abutment sealing area in rear thereof in the sense of rotation comes into the position in which it has its maximum area of engagement with the appropriate sealing area in the contiguous abutment receiving recess, whereby the rotational speed of the rotor for a fixed rate of flow is maintained substantially constant at all angular positions of the rotor and vice versa.

3. A rotary pump or motor of the kind referred to as claimed in claim 2 in which the rotor has four blades and the abutment has four blade-receiving recesses and the circumferential width of each sealing area on the abutment between the adjacent edges of adjacent blade receiving recesses is equal to the sum respectively of the circumferential width of each of the non-sealing areas of the abutment receiving recesses and the circumferential width of each of the sealing areas in the abutment receiving recesses.

4. A rotary pump or motor as claimed in claim 3 in which passages are provided in the abutment whereby each pair of diametrically opposite non-sealing areas both in the abutment and in the abutment receiving recesses are maintained continuously in communication with one another.

5. A rotary pump or motor of the kind referred to as claimed in claim 2 in which the rotor has two blades and the abutment has two blade-receiving recesses with two non-sealing areas and three sealing areas on each of the two circumferential surfaces of the abutment extending

between the recesses, and the larger abutment receiving recess has two non-sealing areas each lying diametrically opposite to and having the same circumferential width as one of the spaces through which the abutment is subject to the pressure in the working chamber, and in which the circumferential length of each of the sealing areas in the larger abutment receiving recess is equal to the circumferential width of the smaller abutment receiving recess and to the sum of the circumferential width of each of the blade receiving recesses and the circumferential width of one of the sealing areas on the abutment.

6. A rotary pump or motor as claimed in claim 5 in which passages are provided in the abutment whereby each pair of diametrically opposite non-sealing areas both in the abutment and in the abutment receiving recesses are maintained continuously in communication with one another.

7. A rotary pump or motor of the kind referred to as claimed in claim 1 in which the rotor has three blades and the abutment has three blade-receiving recesses with a non-sealing area on the part of the circumference of the abutment between each adjacent pair of blade-receiving recesses, the larger abutment receiving recesses has two non-sealing areas lying respectively diametrically opposite to and having the same circumferential width as each of the spaces through which the abutment is subject to the pressure in the working chamber, and in which the circumferential width of each of the sealing areas in the larger abutment receiving recess and of the sealing area of the small abutment receiving recess is equal to the sum of the circumferential width of each of the blade receiving recesses and the circumferential width of each of the sealing areas on the abutment.

8. A rotary pump or motor as claimed in claim 7 in which passages are provided in the abutment whereby each pair of diametrically opposite non-sealing areas both in the abutment and in the abutment receiving recesses are maintained continuously in communication with one another.

9. A rotary pump or motor as claimed in claim 1 including a closed pressure casing enclosing the working parts of the pump, arranged to be maintained full of working liquid and into which the working clearances at the ends of the rotor and abutment open.

10. A pump or motor as claimed in claim 9 wherein the abutment has a hub which extends axially from the abutment chamber and by which the abutment is driven, said hub having a working clearance between it and the surrounding casing, and a circumferentially extending pressure seal arranged in said working clearance.

11. A pump or motor as claimed in claim 2 wherein the abutment has a hub which extends axially from the abutment chamber and by which the abutment is driven, said hub having a working clearance between it and the surrounding casing, and a circumferentially extending pressure seal arranged in said working clearance.
